Primary Examiner — Michelle E. Wilson*Assistant Examiner* — Clese Moore, Jr.(74) *Attorney, Agent, or Firm* — Cislo & Thomas, LLP(57) **CLAIM**

The ornamental design for a wearable blanket, as shown and described.

DESCRIPTION

FIG. 1 is a perspective view of my wearable blanket;

FIG. 2 is a front view thereof;

FIG. 3 is a rear view thereof;

FIG. 4 is a right side view thereof;

FIG. 5 is a left side view thereof;

FIG. 6 is a top view thereof; and,

FIG. 7 is a bottom view thereof.

The dash-dot-dash broken line portions of the disclosure are included for the purpose of illustrating environment and form no part of the claimed design.

The dash-dash broken lines shown in the drawings illustrate portions of my wearable blanket that form no part of the claimed design.
